EXPULSION-TYPE EXCESS-VOLTAGE
PROTECTIVE DEVICE

Otto Ackermann, Irwin, Pa., assignor to Westinghouse Electric & Manufacturing Company, East Pittsburgh, Pa., a corporation of Pennsylvania

Application January 7, 1942, Serial No. 425,902

3 Claims. (Cl. 175—30)

My invention is an improvement in expulsion-arc protective tubes of the general type in which a line-conductor is protected against excess-voltage surges by producing an arc within a restricted space within insulating gas-evolving material which is capable of evolving deionizing gases or particles in the presence of an electric arc.

The principal object of my invention is to both cheapen the cost of manufacture of such a tube, and improve its operating characteristics, these objects being accomplished by a simplification in the mechanical construction, and by the provision of a loosely disposed tube or filler of gas-evolving insulating material disposed in the arcing-space within the protective tube in such manner that the filler is free to move a certain amount axially, radially, and rotatively about its axis, within the bore of the insulating gas-evolving tube of the protective device.

Protective tubes have been made, heretofore, with insulating fillers which are non-movably mounted within the insulating tube of the device, as shown in the original Torok Patent No. 2,050,397 of August 11, 1936, which is the original patent on the type of protective device to which my invention generically relates, and as is shown also in my most recent Patent No. 2,247,352, granted July 1, 1941, on this general type of tube. Experience has shown that consecutive discharges usually pick the same channel in such protective devices, that is, the arcs follow the same line along the walls of both the tube and the plug or filler, eroding them badly along this one line, and making no use of the rest of the material which is offered for volatilization or gas-evolution. This is probably due to the tendency of the arc to move to the path of the least deionizing action, which naturally would be the one which has already been enlarged and partly deprived of deionizing matter by a preceding discharge.

At the same time, the plugged type of protective tube is highly desirable by reason of the very definite current-limiting characteristic which is obtained in the long, highly restricted or narrow annular slot between the gas-evolving tube and the gas-evolving filler or plug, which produces a high arc-drop which has the property of increasing its resistance or voltage-drop as the gaseous pressure builds itself up within the device, so much so, that after a time which may be of the order of 1000 micro-seconds, or considerably less than a half-wave of the 60-cycle line voltage, the power-voltage crest can maintain an arc of only a few hundred amperes, or other lim-

ited current-value which can readily be completely extinguished by the protective device at the first current-zero. Such plug-filled protective tubes are very desirable, therefore, in inherently producing at least a partial current-limiting property which limits the magnitude of the power-follow current which usually flows through the arc for the rest of the half-cycle after a momentary lightning-discharge; and this current-limiting function avoids the necessity for a series resistor, even on power-lines of very large short-circuit capacity.

It is an object of my present invention to avoid the eroding difficulties which have been experienced with previous plugged protective tubes by building the plug or filler so that it is free to resiliently rebound in an axial direction, after a discharge, and at the same time to randomly rotate itself, as a result of the mechanical reaction from the discharge, so that, when the plug or filler settles down again after a discharge, the line in its surface along which the arc had travelled is no longer disposed opposite to the line marked by the same arc along the bore of the tube. This action greatly reduces the qualities (such as roughening traces of carbonization, increased cross-section, etc.) which may render any one path preferable to a subsequent arc. Moreover, if such arc-facilitating features should still exist at all, they are now present at two or more locations. This feature tends to distribute the discharges, which any one protector encounters during its life, more or less uniformly along the periphery of its bore and filler, and it actually produces a quite uniform wear of both.

Further objects of my invention relate to constructional details of the protective tube, and the employment of a single insulator for both the expansion-gap tube and the series gap which is invariably connected in series therewith.

With the foregoing and other objects in view, my invention consists in the structures, apparatus, parts, methods, and systems hereinafter described and claimed and illustrated in the accompanying drawing, wherein:

Figure 1 is a vertical longitudinal sectional view through a so-called heavy-duty tube embodying my invention for use on 6900-volt distribution circuits having unlimited, or very large, short-circuit currents; and

Fig. 2 is a similar view of a second form of embodiment for systems whose fault-current is limited.

The heavy-duty protective tube shown in Fig. 55 1 comprises a main insulating tube 3 of fiber

or other insulating gas-evolving material which is capable of evolving deionizing gases or particles in the presence of an electric arc. This tube is preferably mounted in a vertical position, and is preferably cylindrical, both as to its outer surface and its inner bore. A cylindrical steel rod 4 extends part-way into the top end of the insulating tube 3, to constitute the upper electrode of my protective tube. The bottom end of the steel rod 4 is screwed into a steel electrode-tip 5 which has a tight press-fit within the bore of the main insulating tube 3. A smaller insulating tube 6 surrounds the rod 4 above the electrode-tip 5, and this smaller insulating tube 6 also has a tight press-fit within the bore of the main insulating tube 3. The upper end of the steel rod 4 extends above the device and terminates in a clamp 7 for engaging the line-conductor 8 which is to be protected against excess-voltage surges.

The bottom portion of the main insulating tube 3 is surrounded by a strong steel tube 10 into which the insulating tube 3 is pressed with a tight press-fit. The steel tube 10 preferably extends slightly below the lower end of the main insulating tube 3, to constitute the lower electrode of my protective tube; and the upper end of the steel tube 10 preferably extends higher than the lower end of the upper electrode 4-5, so as to strongly reinforce that portion of the insulating tube 3 which surrounds the lower extremity of the upper electrode.

In accordance with my invention, I provide a loose plug and filler 11 which is disposed underneath the upper electrode 5, with a limited amount of free movement within the lower portion of the main insulating tube 3. This filler 11 is preferably made up of an outer fiber tube 12 having a tight press-fit on an inner fiber bar or rod 13, the bottom end of which is threaded to receive a steel tip 14 for protecting the bottom end of the fiber plug or filler from chipping off or breaking. The outer diameter of the filler 11 is slightly less than the bore-diameter of the main insulating tube 3, to provide a long narrow annular gap-space therebetween, having a lateral or radial depth of the order of $\frac{1}{2}$ of an inch, or other dimension suitable for building up considerable gaseous pressure and a considerable arcing-voltage during the power-follow part of an arcing discharge of the protective device.

The bottom end of the plug or filler 11 rests on a steel pin 15 which is carried by the steel tube 10 at the bottom end of the main insulating sleeve 3. The length or height of the fiber plug or filler 11 is such as to be spaced by about $\frac{1}{8}$ of an inch, or other suitable spacing, from the bottom end of the upper electrode-tip 5, so that the plug or filler 11 is free to have a certain amount of longitudinal movement or rebound, within the main insulating tube 3, and also so as to provide a free arcing chamber 16 between the upper end of the plug 11 and the lower end of the upper electrode 5, which may have a beneficial function in distributing the arc around different portions of the periphery of the inner plug or filler 11.

As in my previous patent, hereinabove mentioned, it is necessary, in the particular design shown, to properly insulate the upper end of the steel tube 10 so as to prevent the occurrence of external flashovers outside of the main insulating tube 3. For this purpose, a thin insulating tube 18 is sleeved over the top of the steel tube 10, so as to extend on up as far as the top of

the main insulating tube 3, and the annular space between these two insulating tubes 18 and 3, above the top of the steel tube 10, is filled with an insulating compound 19 which is of a type that will adhere to, or wet, the surfaces of both of the insulating tubes 18 and 3, and also of such character that it will not harden and crack, producing voids at low temperature. The insulating compound which is commonly used for standard condenser-bushing assemblies is suitable for this purpose.

In the particular form of embodiment of my invention which is shown in Fig. 1, I also provide an additional outer tubular insulating-
15 means 21, in the form of a porcelain insulator which surrounds the upper portion of the protective device. The porcelain insulator 21 has a closed top end 22 which is perforated at 23 to receive the top portion of the steel rod or upper electrode 4. The open lower end of the porcelain insulator 21 is spaced from the steel tube 10 by means of a washer 24 which is welded at 25 to the steel tube 10.

My heavy-duty protective device which is shown in Fig. 1 is supported by means of a grounded conducting supporting-bracket 26 which is in mechanical engagement with the outer porcelain insulator 21, for supporting the protective tube in a vertical position beneath the overhead line conductor 8. The supporting-bracket 26 is provided with an arc-gap electrode-means 27 which is in electrical connection with said bracket and which extends into a spaced-gap relation 28 with respect to the steel tube or lower electrode 10, so as to provide a series gap 28 between the lower electrode 10 and the ground-connection of the bracket 26, which is indicated at 29.

In the operation of the device which is shown in Fig. 1, when the line 8 is subjected to an excess-voltage surge, an arc is produced between the bottom surface of the upper electrode-tip 5 and the bottom portion of the steel sleeve 10, the arc passing first through the open space 18 above the filler 11, and then through the long narrow annular space between the filler 11 and the bore of the main insulating tube 3, thence passing below the insulating tube 3 to the steel sleeve or bottom electrode 10, or possibly making contact 45 with the steel cross-pin 15 which is in engagement with the bottom electrode 10. As explained in my above-mentioned patent, the reinforcing metal sleeve 10 also serves as a shield, facilitating the breakdown of the internal arcing-path just 55 described. At the same time, an external arc flashes across the external gap-space 28 to the bracket-electrode 27, thus completing the circuit to ground at 29.

The excess-voltage surge on the line-conductor 8 usually lasts a relatively short number of microseconds, during which time the discharge may be very heavy, depending upon the severity of the lightning-stroke or other disturbance causing the excess-voltage condition. When this 60 excess-voltage surge is dissipated, the line-voltage reappears across the arcs within and without the tube, usually resulting in what is known as a power-follow current-flow, dependent upon the ability of the line to deliver a short-circuit current, and also depending upon the resistance of the arc within the insulating tube 3.

The initial momentary surge-discharge, and the usually much longer power-follow discharge, both produce gas-evolution from the fiber surfaces which are subjected to the play of the arc

within the protective device, and these evolved gases build up tremendous gas-pressure within the main insulating tube, tending strongly, not only to burst the tube, but also to blast out everything in the tube, including both the upper electrode 4—5—6, and the filler or plug 11 and the outer metal sleeve to which they are pinned. The insulating tube 3 is protected against bursting by the strong steel tube 10, and at the same time the gas-pressure within the insulating tube presses the outer walls of the insulating tube so strongly against the steel tube that axial displacement between the two is substantially an impossibility. Experience has shown that my design is adequate to withstand the tremendous mechanical forces of the gaseous pressures which are developed within the main insulating tube 3 during a discharging operation of the device.

The deionizing properties of the evolved gases result in a cumulative increase in the electrical resistance, or in the voltage-drop required by the arc within the tube, thus developing a current-limiting action which limits the power-follow current which can be delivered by the line-voltage following a momentary lightning-discharge. The result of these actions, is that the arcs are extinguished at the first current-zero following an excess-voltage discharge, and the device is capable of handling the heaviest lightning discharges, and the heaviest short-circuit currents which any line of the proper voltage-rating is capable of delivering.

During a discharge, as above noted, the filler 11 is pressed very strongly against its retaining-pin 15. After the internal gaseous pressure has been dissipated, the filler 11 rebounds from the pin 15, and perhaps chatters around in its space a bit, so that it becomes rotated away from its former position, and the next discharge does not find a discharge-channel of such marked preference and reduced clearing-ability as would exist if the filler had remained in its original position.

The form of embodiment of my invention which is shown in Fig. 2 is designed for distribution-circuits having a limited short-circuit capacity of not over 500 amperes R. M. S. It's similar to the heavy-duty tube which is shown in Fig. 1, except for details of the supports, the omission of the porcelain insulator 21, and a shortening of the axial length of the discharge-space within the main insulating tube 3' below the lower tip 5' of the upper electrode 4'. In the form of embodiment of my invention as shown in Fig. 2, the upper electrode 4' takes the form of a steel bolt whose head 31 is engaged by a metal terminal-cap 32 which is screwed down into engagement with the bolt-head. The terminal-cap 32 also carries an arc-gap electrode-means or rod 33 which extends in a spaced-gap relation below the overhead line-conductor 8' which is to be protected, thus providing an external gap 28' between said overhead line-conductor 8' and the arc-gap rod 33 at the top of the protective tube.

The supporting-means for the protective tube which is shown in Fig. 2 is in the form of a grounded supporting-bracket 35 which is grounded at 36, and which is bolted to the lower end of the steel tube 10'.

The operation of the device shown in Fig. 2 is similar to the operation of the more elaborate device which is shown in Fig. 1, except that the series arc 28' is formed between the upper electrode 4' and the line-conductor 8', instead of at the grounded end of the device, as in Fig. 1. The shorter length of the fiber plug or filler

somewhat reduces the resulting arc-voltage, thus permitting relatively higher power-follow current. This, however, does not detract from the value of the device as a means for overvoltage-relief as long as it is applied to systems which can not deliver short-circuit currents which would too quickly erode the tube. In view of this limitation, I prefer to give a conservative rating to the device shown in Fig. 2, for instance, rating it for use only on systems whose fault-current is not over 500 amperes, R. M. S.

While I have illustrated and described my invention in two forms of embodiment which are at present preferred by me, I wish it to be understood that such illustration and description are only by way of example and not by way of limitation, as various changes may be made by those skilled in the art without departing from the essential features of my invention. I desire, therefore, that the appended claims shall be accorded the broadest construction consistent with their language.

I claim as my invention:

1. An expulsion-type excess-voltage protective device comprising an insulating tube having a cylindrically bored surface of insulating gas-evolving material capable of evolving deionizing gases or particles in the presence of an electric arc, a loose filler disposed for a limited amount of free movement within said insulating tube, said filler having an outer cylindrical surface of insulating gas-evolving material capable of evolving deionizing gases or particles in the presence of an electric arc, the outer diameter of the filler being slightly less than the bore-diameter of the tube, abutment-means for limiting the axial movement of the filler in the tube to a small but appreciable amount, while otherwise leaving the filler free to move axially, radially, and rotatively about its axis, within the bore of the tube, and free to come to rest in any position, and two spaced electrodes so disposed that the arc-gap between said two electrodes includes the space between said filler and said bore, at least one of the electrodes extending partway into said bore.

2. An expulsion-type excess-voltage protective device comprising an approximately vertically disposed insulating tube having a cylindrical bored surface of insulating gas-evolving material capable of evolving deionizing gases or particles in the presence of an electric arc, a rod-like upper electrode extending into the top end of the insulating tube with a tight fit therein, a tubular lower electrode of strong metal construction fitting over the lower portion of the insulating tube with a tight press-fit therebetween, said tubular electrode extending below the lower end of the insulating tube and extending up past the portion of the insulating tube that surrounds the lower end of the upper electrode, a loose filler disposed underneath said upper electrode with a limited amount of free movement within said insulating tube, said filler having an outer cylindrical surface of insulating gas-evolving material capable of evolving deionizing gases or particles in the presence of an electric arc, the outer diameter of the filler being slightly less than the bore-diameter of the tube, and abutment-means at the bottom of the insulating tube for supporting the filler so that its top end is spaced below the bottom end of the upper electrode.

3. An expulsion-type excess-voltage protective device comprising an insulating tube having

a cylindrical bored surface of insulating gas-evolving material capable of evolving detonizing gases or particles in the presence of an electric arc, a rod-like electrode extending into one end of the insulating tube with a tight fit between the inner end of said rod-like electrode and the bore of said insulating tube, a tubular electrode of strong metal construction fitting over a portion of the insulating tube at the opposite end thereof, with a tight press-fit therebetween, said tubular electrode overlapping the portion of the insulating tube that surrounds the inner end of the rod-like electrode, a loose filler disposed within said opposite end of the insulating

10 tube, with a limited amount of free movement therein, said filler having an outer cylindrical surface of insulating gas-evolving material capable of evolving detonizing gases or particles in the presence of an electric arc, the outer diameter of the filler being slightly less than the bore-diameter of the tube, and abutment-means at said opposite end of the insulating tube for so limiting the outward axial movement of the 15 filler that the axial distance between the inner ends of the filler and the rod-like electrode may not exceed a predetermined spacing.

OTTO ACKERMANN.
